UNITED STATES PATENT OFFICE

2,487,736

PAPER CUP DISPENSER

Clark D. Sims, Elmhurst, Ill., assignor to Lily-Tulip Cup Corporation, a corporation of Delaware

Application March 2, 1948, Serial No. 12,679

2 Claims. (Cl. 312—43)

1

This invention is directed to cup dispensers for paper cups and is an improvement over the cup dispenser disclosed and claimed in Walter E. Amberg Patent No. 2,369,933, granted February 20, 1945.

As is well known, paper containers such as paper cups are usually sold nested one within the other. It is common practice in the use of such cups to place them in a metal dispenser provided with suitable dispensing elements so that the cups can be withdrawn from the bottom of the stack one at a time. The dispensing of the cups involves a number of problems. In order to dispense the cups satisfactorily, the dispenser must be such that only a single cup is withdrawn from the bottom of the stack when the lowermost cup of the stack is grasped by the hand. It is also desirable that only a slight pull be required in order to remove the lowermost cup of the stack. Usually if a strong pull is necessary, the cup is likely to be damaged.

Prior to the invention of the aforementioned Amberg patent dispensers which were suitable for dispensing relatively flexible cups were not suitable for dispensing stiffer types of cups. The dispenser of the aforementioned Amberg patent, however, was so constructed that both types of cups could be dispensed therefrom provided the rim diameters of both types of cups were substantially the same.

Paper cups are manufactured in many different sizes and it has been necessary to utilize a different sized dispenser for each size of cup, thus requiring many different sized dispensers which must be manufactured, stocked and distributed at relatively great cost. The Amberg patented dispenser referred to above did not satisfactorily dispense paper cups of different sizes and it was necessary to utilize many different sizes thereof for the many different sized cups. The construction and shape of the spring dispensing blades of that patented construction were such that cups of different sizes could not be accommodated and dispensed properly.

The principal object of this invention, therefore, is to provide an improved cup dispenser for accommodating and dispensing paper cups having different rim diameters whereby the number of cup dispensers required to be manufactured, stocked and distributed for accommodating and

2

dispensing the large number of various sized paper cups may be reduced to a minimum.

In carrying out this object of the invention the improved cup dispenser is provided with improved 5 spring fingers whereby various sized cups may be readily accommodated and resiliently held in the dispenser and yet wherein the cups may be individually dispensed with substantially the same effort regardless of the cup size. The spring 10 fingers are so constructed and shaped and disposed with respect to each other that the resiliency thereof and the action thereof on the paper cups are predetermined to provide an automatically adjustable restricted dispensing throat 15 to accomplish these results.

Further objects of this invention reside in the details of construction of the cup dispenser and the cooperative relationship between the component parts thereof.

20 Other objects and advantages of this invention will become apparent to those skilled in the art upon reference to the accompanying specification, claims and drawings in which:

Figure 1 is a side elevational view of the cup 25 dispenser;

Figure 2 is a plan view of Fig. 1 with the cups omitted;

Figure 3 is a front elevational view of one of the spring fingers utilized in the cup dispenser;

30 Figure 4 is a side elevational view of the spring finger;

Figure 5 is a vertical sectional view through the cup dispenser taken substantially along the line 5—5 of Fig. 2 and showing relatively large cups 35 accommodated therein;

Figure 6 is a bottom view of Fig. 5;

Figure 7 is a view similar to Fig. 6 and showing one of the relatively large sized paper cups being dispensed.

40 Figure 8 is a sectional view similar to Fig. 5, but showing relatively small sized cups being accommodated in the cup dispenser;

Figure 9 is a bottom view of Fig. 8, and

45 Figure 10 is a view similar to Fig. 9, but showing one of the small sized cups being dispensed.

The cup dispenser is generally designated at 10 and includes a substantially cylindrical tubular member 11 for holding a stack of cups, a bracket 12 is secured to the dispenser for mounting purposes. The tubular member may be formed of

two parts, the upper part 11 and a lower part 13, the latter being provided with a flange 14 for receiving the former. The two parts may be spot welded together at the flange 14. For convenience the upper part of the tubular member may have an open portion so that the paper cups may be readily loaded therein and so that the number of cups contained within the dispenser may be visually determined. The bottom portion 13 of the substantially cylindrical tubular member provides a dispensing area through which cups may be dispensed from the bottom of the stack one at a time.

The substantially cylindrical tubular member including the dispensing area is of such size that cups of different rim diameters may be accommodated therein, for example, cups 15 having rims 16 of large diameters as illustrated in Figure 5 or cups 31 having rims 32 of relatively small diameters as illustrated in Figure 8.

A plurality of spring fingers 18 are circumferentially located and secured in the dispensing area 13 of the tubular member. As illustrated four such spring fingers are utilized. Each spring finger 18 is provided with a longitudinal concave inner surface 19, the radius of the concavity being less than the radius of the tubular member. The side portions of the lower end of the spring fingers are bent outwardly at 20 to provide outwardly extending portions 21 and the ends of the outwardly extending portions 21 are in turn bent forwardly to provide portions 22 for engaging the tubular member. The spring fingers are relatively resilient and in this respect are formed from stainless steel. Preferably, the spring fingers are provided with a central detent 23 for the purpose of maintaining the stainless steel fingers in the desired shape as illustrated in Figs. 3 and 4. The upper end of the spring fingers are provided with holes 24 through which the spring fingers are secured to the tubular member by rivets 25.

When the spring fingers 18 are secured within the dispensing area of the tubular member, the upper ends thereof are held against the tubular member by the rivets 25 and the extending portions 22 engage the tubular member whereby there is provided an inwardly and downwardly concave sloping surface intermediate the ends thereof.

When a stack of paper cups is inserted in the dispenser, the rim of the bottom paper cup engages the inwardly and downwardly sloping surfaces of the spring fingers. The spring fingers flex to an extent depending upon the size and weight of the cups, the flexing being permitted by the portions 22 thereof sliding on the tubular member. Because the portions 22 slidably engage the tubular member the resiliency of the fingers may be accurately predetermined.

When the paper cups 15 of relatively large rim diameters are thus accommodated in the dispenser, the rim of the bottom cup will assume a position "A" relatively high up on the spring fingers 18 as illustrated in Fig. 5. To dispense the bottom cup from the stack of cups all that is necessary is to grasp the bottom cup and pull the same downwardly. When this is done the rim 16 of the paper cup is deformed somewhat as is illustrated in Fig. 7. When the cup is dispensed the rim thereof immediately snaps back to its original condition. As shown in Fig. 7, temporary deformation of the rim of the paper cup is permitted since the rim enters the concave portion of the sloping surfaces of the fingers, and also, enters between the fingers. In this way the

rim of the paper cup may be temporarily and uniformly deformed a slight amount without danger of permanently deforming and allowing the rim to snap back to its original condition.

Figures 8, 9 and 10 disclose the dispenser accommodating a stack of paper cups having relatively small rim diameters and in this respect it is noted that the rim 32 of the bottom cup 31 engages the sloping surfaces of the spring fingers at point "B" which is somewhat lower than point "A" in Fig. 5. The manner of dispensing these relatively small cups is substantially the same as that of dispensing the larger cups, as is clear by a comparison of Figs. 9 and 10 with Figs. 6 and 7.

The inwardly and downwardly sloping concave surfaces of the spring fingers are automatically positioned by the stack of cups placed in the dispenser to provide an automatically adjustable restricted dispensing throat in the dispensing area of the tubular member so that various sized cups may be readily accommodated in the dispenser and so that such various sized cups may be readily dispensed therefrom with substantially the same degree of effort.

When it is desired to remove cups from the dispenser by pick up holder a substantially conical weight 27 is placed on the stack of cups for holding the stack firmly in the dispenser. The weight 27 may be connected by a chain 28 to the tubular member at 29 to prevent loss thereof. The weight holds the stack in position when the pick up holder is forced over the bottom cup of the stack for gripping the bottom cup to remove it from the stack.

While for purposes of illustration one form of this invention has been disclosed other forms thereof may become apparent to those skilled in the art upon reference to this disclosure, and therefore, this invention is to be limited only by the scope of the appended claims.

I claim as my invention:

1. A cup dispenser for accommodating and dispensing paper cups having different rim diameters comprising, a substantially cylindrical tubular member for holding a stack of cups and having an internal diameter of such size for receiving stacks of cups of different rim diameters and having a dispensing area at the lower end thereof through which cups may be dispensed from the bottom of the stack one at a time, and a plurality of spring fingers circumferentially located and secured in the dispensing area of the tubular member to provide an automatically adjustable dispensing throat, each spring finger being formed to provide a longitudinal concave inner surface and being longitudinally arranged in the dispensing area with its upper end secured to the tubular member and with the side portions of the lower end bent outwardly for engaging the tubular member to provide an inwardly and downwardly concave sloping surface intermediate its ends for engaging the rims of the cups at points along the sloping surface dependent upon the rim diameters of the cups to support the stack of cups in the tubular member, the outwardly bent side portions of the spring fingers sliding on the tubular member to provide for flexing thereof to obtain the automatically adjustable dispensing throat.

2. A cup dispenser for dispensing paper cups comprising, a substantially cylindrical tubular member for holding a stack of cups and having a dispensing area at the lower end thereof through which cups may be dispensed from the bottom of the stack one at a time, and a plurality of spring

fingers circumferentially located and secured in the dispensing area of the tubular member, each spring finger being formed to provide a longitudinal concave inner surface and being longitudinally arranged in the dispensing area with its upper end secured to the tubular member and with the side portions of the lower end bent outwardly for engaging the tubular member to provide an inwardly and downwardly concave sloping surface intermediate its ends for engaging the rims of the cups to support the stack of cups in the tubular member, the outwardly bent portions of the spring fingers sliding on the tubular member to provide for flexing thereof.
